UNITED STATES PATENT OFFICE.

WILLIAM W. THOMPSON, OF CHICAGO, ILLINOIS.

SWITCHING DEVICE.

1,382,029.

Specification of Letters Patent. Patented June 21, 1921.

Application filed April 12, 1919. Serial No. 289,533.

To all whom it may concern:

Be it known that I, WILLIAM W. THOMPSON, a citizen of the United States, residing at Chicago, in the county of Cook and State 5 of Illinois, have invented a certain new and useful Improvement in Switching Devices, of which the following is a full, clear, concise, and exact description, reference being had to the accompanying drawings, forming 10 a part of this specification.

My invention relates to signaling systems and has for its object the provision of a signaling system which may be used on telegraph lines or other lines already provided 15 with signaling or similar instruments.

The object of my invention is to provide signaling means which are of such a character that they can be placed upon lines of this general nature and perform their functions uninfluenced by the functioning of the 20 other devices upon the line, and in turn performing their functions without influencing these other devices which are upon the line.

In those cases where my invention is applied to a telegraph line, whose instruments usually operate by low frequency current impulses, and which line may also serve for telephonic purposes, my improved signal receiving device would be so constructed as to 25 be responsive to a frequency above the frequency of the telegraphic impulses. The device may then be so arranged that it responds at a frequency lower than that of the telephonic current or it may be so adjusted that 30 the weak telephonic currents, even though of a frequency calculated to operate my device, would leave it uninfluenced due to their lack of strength. Under such conditions I find it quite practical to arrange my signal receiving device so that it is responsive to a 35 current furnished from a transformer coil having primary and secondary windings, the primary winding having a vibratory element in its circuit in addition to a battery. Such a signal sending device is 40 commonly used in connection with telephones, by which I mean telephone instruments adapted for operation upon a telegraph line.

50 My improved signal receiving device is arranged to properly respond to such a signaling current, such signaling current being of a frequency higher than would operate the telegraph instruments upon the line.

I will describe this particular form which 55 my invention may take more in detail by referring to the accompanying drawings, in which—

Figure 1 is a front view of a signal receiving device constructed in accordance with 60 my invention as mounted in a box;

Fig. 2 is a sectional view on line 2—2 of Fig. 1;

Fig. 3 is a sectional view on line 3—3 of Fig. 2;

Fig. 4 is a sectional view on line 4—4 of Fig. 1, and

Fig. 5 is a diagrammatic view illustrating a form of circuit arrangement.

Referring more particularly to Fig. 1, I 70 show a signal box 10 having a plurality of binding posts 11, 12, 13, 14, 15 and 16, which box may be provided with the customary cover 17. A condenser 18 is mounted within the box and also a relay 19. There is further mounted in this box a vibratory contact 75 controlling device 20 forming part of my improved signal receiving device. The relay 19 has an armature 21 provided with a contact 22 which coöperates with a fixed contact 23. A suitable front stop 24 is provided. This relay operates in connection with the vibratory contact controlling device 20.

To more readily understand the functions 85 to be performed by these various devices, I will explain the circuit conditions involved by referring more particularly to Fig. 5, in which two line wires 25 and 26 are illustrated, although one of the line wires, of course, may be replaced by the ground, if desired. This line circuit coöperates with 90 telegraph instruments diagrammatically indicated at 27 and 28. A telephone 29 is also shown connected to the line, only one such telephone being shown as typical of a number which are connected to the same line circuit. This telephone has the talking instrumentalities 30 and the signaling instrumentalities 31, the signaling instrumentalities including the primary winding 32, secondary winding 33 and vibratory control element 34 movable in response to the energizations of the coil 32, a battery 35 and a key 36. Whenever the key 36 is depressed, 95 high frequency currents are transmitted over the line circuit, as will be readily apparent. These high frequency currents are designed 100

to actuate the signal bell 37 which forms part of my improved signal receiving circuit structure 38. The structure 38 with the exception of the bell 37 is illustrated in detail 5 in Figs. 1, 2, 3 and 4. It will be noted that the vibratory signal controlling device 20 includes a diaphragm 39 having a contact 40 which co-operates with a second contact 41 carried by a movable arm 42 pivotally 10 mounted at 43 and moved to its normal position by the spring 44. The relay 19 has its circuit normally closed and is energized through the agency of a source of current 45 which is herein illustrated as a battery, but 15 which in the preferred form is the regular 110 volt circuit. The circuit of the relay 19 thus extends from the source of current 45 by way of conductor 46, relay 19, conductor 47, arm 42, contacts 41 and 40, diaphragm 20 39, conductor 48, to the source of current 45. As the contacts 40 and 41 are normally closed, the relay 19 normally maintains the circuit between the elements 22 and 23 open so that 25 the bell 37 is normally not operating. The bell 37 is included in a local circuit including the battery 49, the contacts 22 and 23, and the armature 21.

Now, whenever a high frequency current of the character emitted by the signal sending device 31 travels over the line circuit, this high frequency current vibrates the diaphragm 39, thus breaking the contacts between the elements 40, 41, in accordance with the vibrations of the diaphragm 39. These 30 rapid breaks and makes of the circuit through the elements 40 and 41 are sufficient to cause the relay 19 to release its hold upon the armature 21 and to maintain a permanent closure between the contacts 22 and 23 35 during the time of the vibrations of the diaphragm 39. The winding of the relay 19 is such that there is a very small flow of current therethrough (in the particular instance under discussion about four milli- 40 amperes) and the momentary breaks in the circuit are sufficient so long as these breaks continue to prevent the relay 19 from drawing up its armature 21.

It will be understood that the high frequency current emanating from the device 31 can not satisfactorily directly actuate the relay 19 which directly controls the bell or signal receiving device 37, for the reason that if these currents were of a sufficient 45 strength to cause the relay 19 to attract its armature, that then the armature 21 would chatter and there would be no certainty that the vibratory signal 37 would respond with any degree of definiteness to indicate the receipt of a signal. This is true of all local 50 circuits where there are two vibratory elements, as interference between them is the usual rule.

It will be understood, of course, that the 55 signal receiving device 37 may be replaced

by a telegraph sounder or other similar instrument, in view of the fact that the relay 19 permits permanent retraction of its armature during the period of vibration of the diaphragm 39.

My invention further contemplates a peculiar construction of the vibratory signal receiving device 20 in order to make it most effective for the particular kind of current emitted by devices such as the device 31.

By referring more particularly to Figs. 1, 2, 3 and 4, the device 20 includes a casing 50 having an annular collar 51 screw threaded thereto and clamping in position the diaphragm 39. This diaphragm as already explained, carries a contact element 40 to co-operate with a contact element 41 carried upon the arm 42. Within the casing electromagnets 52 are provided which when energized by fluctuating or intermitting current 55 vibrate the diaphragm 39 in harmony with such fluctuations or alternations. The arm 42 is pivotally mounted as indicated at 43 and is under the control of the spring 44 which tends to move it in a contra-clockwise direction (Fig. 1). This spring has its right hand extremity secured to a cord 53, which cord is wound up by means of the finger piece 54 so as to adjust the tension of the said spring. The arm 42 likewise carries a thin leaf spring 55 which is fixedly mounted upon the upper extremity of this arm 42 and this thin leaf spring has its tension controlled by the set screw 56. These two adjustments make it possible to secure the particular kind of vibratory movement between the contacts 40 and 41 that is necessary in order to secure the proper operation of the relay 19. The advantages of this device will be readily apparent in that non-interfering 95 multiple signaling may be carried on over the ordinary telegraph circuit.

My invention of course is applicable to a multitude of uses and its illustration herein as designed to effect the ultimate operation 100 of the signaling bell 37 must not be confined to limiting it to such particular use.

Having however thus described one form which my invention may take, what I claim as new and desire to secure by Letters Patent is:

1. A relay of the character described comprising an electro-magnet, a vibratory armature therefor, a circuit controlling element movable therewith, a co-operating circuit controlling element, and means for pressing said circuit controlling elements together, said means including a relatively strong spring and a relatively light spring.

2. A relay of the character described comprising an electro-magnet, a vibratory armature therefor, a circuit controlling element movable therewith, a co-operating circuit controlling element and means for pressing said circuit controlling elements together, said

means including a relatively strong spring and a relatively light spring acting cumulatively.

3. A relay of the character described comprising an electromagnet, a vibratory armature therefor, a circuit controlling element movable therewith, a coöperating circuit controlling element and means for pressing said circuit controlling elements together, said means including a relatively strong spring and a relatively light leaf spring.

4. A relay of the character described comprising an electromagnet, a vibratory armature therefor, a circuit controlling element movable therewith, a coöperating circuit controlling element, and means for pressing said circuit controlling elements together, said means including a relatively strong coiled spring and a relatively light leaf spring.

5. A relay of the character described comprising an electro-magnet, a vibratory diaphragm armature therefor, a circuit controlling element movable therewith, a coöperating circuit controlling element, and means for pressing said circuit controlling elements together, said means including a relatively strong spring and a relatively light spring.

6. A relay of the character described comprising an electro-magnet, a vibratory diaphragm armature therefor, a circuit controlling element movable therewith, a coöperating circuit controlling element, a swinging arm upon which said coöperating element is mounted, and means for pressing said circuit controlling elements together, said means including a relatively strong spring and a relatively light spring.

7. A relay of the character described comprising an electro-magnet, a vibratory diaphragm armature therefor, a circuit controlling element movable therewith, a coöperating circuit controlling element, a swinging arm upon which said coöperating

element is mounted, and means for pressing said circuit controlling elements together, said means including a relatively strong spring and a relatively light spring, said springs acting cumulatively upon said arm.

8. A relay of the character described comprising an electro-magnet, a vibratory armature therefor, a circuit controlling element movable therewith, a coöperating circuit controlling element, means for pressing said circuit controlling elements together, said means including a relatively strong spring and a relatively light spring acting cumulatively, and means for adjusting the tension of said springs.

9. A relay of the character described comprising an electro-magnet, a vibratory armature therefor, a circuit controlling element movable therewith, a coöperating circuit controlling element, means for pressing said circuit controlling elements together, said means including a relatively strong coiled spring and a relatively light leaf spring, a set screw for adjusting the tension of said leaf spring and means for adjusting the tension of said coil spring.

10. A relay of the character described comprising an electro-magnet, a vibratory armature therefor, a circuit controlling element movable therewith, a coöperating circuit controlling element, means for pressing said circuit controlling elements together, said means including a relatively strong coiled spring and a relatively light leaf spring, a set screw for adjusting the tension of said leaf spring and means for adjusting the tension of said coil spring, said means comprising a flexible member secured to one end of said coil spring, and a member about which said flexible member is adapted to be wound.

In witness whereof, I hereunto subscribe my name this 4th day of April, A. D. 1919.

WILLIAM W. THOMPSON.
